(57) **CLAIM**

The ornamental design for a pneumatic tire, as shown and described.

DESCRIPTION

FIG. 1 is a perspective view of a pneumatic tire incorporating our new design, it being understood that the tread pattern repeats circumferentially throughout the outer circumference;

FIG. 2 is an elevational view of one end of the pneumatic tire shown in FIG. 1;

FIG. 3 is an elevational view of the opposite end of the pneumatic tire;

FIG. 4 is an elevational view of one side of the pneumatic tire shown in FIG. 1;

FIG. 5 is an elevational view of the opposite side of the pneumatic tire; and,

FIG. 6 is a fragmentary view of FIG. 2.

The broken lines in the drawings depict environmental subject matter only and form no part of the claimed design.
